LOCOMOTIVE CRANE

John R. McGiffert and Norman Huber, Duluth,
Minn., assignors to Clyde Iron Works, Duluth,
Minn., a corporation of Maine

Application November 27, 1929, Serial No. 410,103

7 Claims. (Cl. 105—28)

This invention as indicated relates to locomotive cranes, and has more particular reference to the type of cranes employed in handling logs and for accomplishing like objects. The objects 5 of our invention briefly stated are to provide a machine having an improved arrangement of the operative parts as well as a novel means for supporting the driving or propelling means of such crane, the improved means presenting none 10 of the undesirable features found in structures now in common usage.

In the construction of cranes of the type above referred to, the drive shaft by means of which the carriage supporting the crane is propelled, 15 must of necessity pass coaxially through the king pin about which the bed of the crane revolves. Considerable difficulty has been experienced in connection with the drive shaft so passing through the king pin due to the fact that 20 when a load of sufficient magnitude is suspended from the boom the equilibrium of the revolute bed will be overcome and the drive shaft passing through the king pin therefor subjected to a bending or shearing force. When the load supported by the boom is sufficient to overcome the 25 equilibrium of the revolute table, the king pin must of necessity be utilized to prevent a tipping of the table and transmit a load to the under carriage.

Further difficulties in crane construction have been experienced in the transmission of the 30 stresses from the boom to the bed and thence to the supporting carriage. In order to properly sustain the heavy boom and its associated load, revolute carriages of the type now commonly 35 employed have been cumbersome and improperly designed from the standpoint of the internal stresses set up therein by the boom.

It is an object of our invention to provide a 40 structure for the revolute bed in which the loads incidental to the manipulation of the boom shall be directly carried by main supporting members forming a portion of the revolute bed structure.

A further object of our invention is to provide 45 a means whereby the above mentioned difficulties incidental to the drive shaft for the carriage passing through the king pin shall be entirely 50 done away with. Other objects of our invention will appear as the description proceeds. To the accomplishment of the foregoing and related ends, said invention, then, consists of the means hereinafter fully described and particularly 55 pointed out in the claims.

The annexed drawings and the following description set forth in detail certain mechanism

embodimenting the invention, such disclosed means constituting, however, but one of various mechanical forms in which the principle of the invention may be used.

In said annexed drawings:

Fig. 1 is a diagrammatic elevation of the machine comprising the principles of our invention; Fig. 2 is a fragmentary diagrammatic side view of the machine shown in Fig. 1; Fig. 3 is a diagrammatic plan view of the revolving bed of the 10 machine shown in Fig. 2; Fig. 4 is a part section part elevation of a portion of the machine shown in Fig. 3; Fig. 5 is a fragmentary part section part elevation of a portion of the machine shown in Fig. 3 taken at right angles to the plane of 15 Fig. 4; Fig. 6 is a part section part elevation of the carriage for the conical rollers.

Referring more specifically to the drawings and more especially to Fig. 1, the machine here illustrated comprises a boom 1 which is connected at its lower end to a revolving bed 2 which has suitably mounted thereon the frame members 3 and 4. The boom 1 is shown held in elevated position by means of the cable 5, the ends of which are secured to drums 88 and 89 respectively, cable 5 passing over pulleys 6 which are revolvably mounted in the oscillatory member 7 secured to the boom 1 at 8. Pulleys 11 and 12 are shown depending from the boom 1, one of such pulleys serving as a means of support for the cable 13 which passes therearound and is wound on the drum 65, the cable 13 being the one which is commonly employed in lifting or otherwise manipulating the heavier work which a crane of this type is called upon to perform. The revolute bed 2 is suitably supported on the annular member 15 which is here shown to be in the form of a large spur gear. The annular member 15 is in turn rigidly supported on the carriage frame structure 16 which is supported by means of the trucks 17 which are in turn supported by the wheels 18 in Fig. 2 shown resting upon the track 19.

Referring to Fig. 3, the sills 20 and 21 which 45 make up the primary load carrying portion of the revolute bed 2 are shown with members 22 integrally united therewith and in alignment with the webs thereof, to which projecting elements 22, the lower ends 23 of the boom 1 are pivotally 50 secured by means of the bifurcated ends 24 and the pins 25 passing through aligned openings in such elements 22 and such bifurcated ends 24. The sills 20 and 21 extending longitudinally of the 55 revolute bed 2 are here shown supporting the

major portion of the boom operating mechanism which will now be explained.

The means for providing the motive power of this machine as well as the prime mover for the drums upon which the cables are wound, is in Fig. 3 diagrammatically represented as a gasoline engine 26 which has its crank shaft 27 extending therefrom and to which is connected a drive shaft 28 by means of the coupling 29. Rigidly mounted on the drive shaft 28 are plural driving means 30 and 31 respectively here shown as common gear wheels. The driving elements 30 and 31 intermesh with driven elements 32 and 33 respectively which are loosely mounted on the shaft 34. Co-axially mounted on the shaft 34 are drums 35 and 36 which have surrounding them frictional clutching members 37 and 38 respectively. Rigidly mounted on the shaft 34 is a driving means 39 which is in communication with a driven means 40 rigidly mounted on the shaft 41, by means of the belt or other suitable means 42. Loosely mounted on the shaft 41 are a plurality of driving means 43 and 44 adapted to rotate with the shaft 41 when the friction means 45 and 46 are respectively clamped on the drums 47 and 48. The driving means 43 and 44 are respectively in communication with the driven means 49 and 50, the gear 44 directly meshes with gear 50, and the gear 43 drives the gear 48 by means of the idler element 51 which is mounted on the shaft 53 and which may be journaled at one end 54 in the side member of the revoluble frame 2 and at the other end in the bearing member 55. The driven means 49 and 50 are rigidly supported on the shaft 56 to which is suitably secured at one end the beveled driving means 57 which is in communication with the beveled driven means 58 more clearly shown on Figs. 4 and 5. The shaft 41 as shown on Fig. 3 has rigidly supported thereon a driving means 59 which is in communication with the driven means 60 and 61 respectively mounted on the shafts 62 and 63. Coaxially mounted with the shafts 62 and 63 are winding drums 64 and 65 which may be respectively caused to rotate by frictionally engaging them with the gears 60 and 61 by operating the thrust screws 91'. The drums 64 and 65 are provided with brakes 68 and 69.

The shaft 62 has loosely supported thereon opposed beveled driving means 70 and 71 which are in mutual contact with the beveled driven means 72 which is fixed on shaft 72a. Shaft 72a is securely mounted in a bearing fixed between beams 72b and 72c. Keyed to the lower end of the shaft 72a is a pinion 72d which meshes with the gear shaped surface of the annular member 15 for rotating the revoluble bed of the machine. Gears 73 and 74 may be alternately driven by shaft 62 by engaging either clutch 70' or clutch 71'.

The driven element 60 which becomes a driving element when in communication with the driven element 73 drives the shaft 74 through such element 73 which is rigidly supported thereon. Co-axially mounted on the shaft 74 are opposed beveled driving elements 75 and 76 respectively which have in communication therewith the beveled clutch elements 77 and 78 adapted to communicate with the complementary elements 79 and 80 as the shaft 74 is axially displaced by means of the sliding element 81 acting in the circumferential groove 82 formed therefor on the shaft 74. As the shaft 74 is axially displaced, one of the beveled driving elements 75 or 76 is brought into communication with the beveled driven element 83 which is rigidly mounted on the shaft 84. The shaft 84 has rigidly mounted thereon the

driving element 85 which is adapted to coact with the driven element 86 for revolving the shaft 87 and its associated winding drums 88 and 89.

The shaft 63 has mounted thereon a sheave 90 which is frictionally engaged to said shaft by means of the tension spring 90' and when a clam shell bucket is being operated by the crane, a line is run from the side of the bucket to this sheave, the tension of the line preventing the bucket from twisting, and the various shafts 34, 41, 62 and 63 have coaxially associated therewith means 91 and 91' hydraulically or otherwise actuating the frictional engaging means for the drums mounted on the respective shafts.

As shown in Figs. 4 and 5, the driving means 57 hereinbefore described as terminally mounted on the shaft 56 which is revolvably supported in the bearing 92 is in communication with the beveled driven member 58 which is coaxially mounted on the vertical drive shaft 93 on which at its other end is mounted beveled driving means 94. The beveled driving means 94 is in communication with a beveled driven means 96 loosely mounted on the shaft 97 which is fixed in supports 98 and 99. The shaft 97 has rigidly mounted thereon a driving means 101 which is formed integrally with beveled means 96, and is in communication with the axles 102 of the trucks 17 by means of the power transmission means 103 and 104.

The trucks 17 have formed thereon annular members 105 adapted to receive the tubular ends 106 of the aligning elements 107 which are mounted at 108 to the carriage frame 16. The carriage frame 16, as shown in Figs. 4 and 5, is composed of built-up structural steel shapes 35 suitably riveted or otherwise joined to provide a suitable means for supporting the annular element 15 and the revoluble bed 7 which rests on such annular element 15. The carriage frame 16 has united therewith, on its lower surface, a member 109 which has laterally extending arms 110 adapted to be connected to the carriage frame 16 and has downwardly extending therefrom arms 111 which provide supports for the members 98 and 99 hereinbefore described. A portion 112 of the member 109 extends upwardly into an aperture 113 formed centrally in the carriage frame 16. Pressed into the portion 112 and rigidly secured thereto is the king bolt 93'. Secured to the sills 20 and 21 of the revoluble bed 2 is a downwardly extending member 114 which is adapted to engage the king bolt 93'.

The downwardly extending member 114 has a circular recess 115 formed centrally of its lower portion, in which are secured a plurality of circumferentially spaced rollers 116 by means of the retaining element 117. Centrally of the upper surface of the member 114 is a square recess 118 adapted to laterally and longitudinally support a block 119. The block 119 in turn supports the thrust bearing 120, which is securely held in place by means of the axially adjustable collar 121 secured to the periphery of the king bolt 93' by means of the screw threads 122. The king bolt 93' is terminally provided with bushings 123 and 124 having circumferential flanges 125 and 126, respectively, adapted to be supported in apertures formed therefor in the ends of the king bolt 93'.

Interposed between the ends of the king bolt 93' and the beveled driven and driving means 58 and 94, respectively, are wearing plates 127 and 128. The beveled driven means 58 is axially secured to the shaft 93 by means of a feather key 58'. The threaded collar 129 provides means for

the proper adjustment between the driving means 58 and the driven means 94, taking up the looseness caused by the wear of plates 127 and 128.

5 The revoluble bed 2 of the machine is supported on the frame 16 of the carriage by means of the annular gear-shaped member 15, as hereinbefore described. This annular member 15 has its upper surface beveled inwardly to receive the 10 conical rollers 130, as diagrammatically illustrated in Fig. 3. The conical rollers 130 are supported and secured in the manner illustrated in Fig. 6. The rollers 130 in Fig. 6 are shown of the type commonly employed and are revolubly 15 mounted by means of oppositely opposed conical rollers 131 which travel in the races 132, the inner race being supported by the shaft 133 which is mounted in the bracket member 134. The shafts 133, upon which the conical rollers 20 130 rotate, are so arranged in the bracket 134 that the axes of such shafts 133 intersect at the vertical axis of rotation of the revoluble bed 2. The bracket 134 is oscillatorily supported by the 25 shaft 135, which is journaled in suitable support members 136 formed on the lower surface of the revoluble bed 2. The shafts 135 for the two forward pairs of rollers are mounted substantially in alignment with sills 20 and 21, respectively, and the third pair of rollers is in the 30 rear centrally between sills 20 and 21.

The operation of the machine will now be briefly described. The power means 26, which 35 may be an internal combustion engine, causes the crank shaft 27 to rotate, which drives the drive shaft 28 through the flexible connection 29 and rotating such shaft 28 causes a rotation of the driven means 32 and 33 at different speeds, due to the fact that the drive means 30 and 31 which, respectively, actuate the driven means 32 and 33 are of different diameter. The driven 40 means 32 and 33 are loosely mounted on the shaft 34 and are permitted to rotate freely thereon until one or the other of the drums 35 or 36 is frictionally engaged by either of the members 45 37 or 38, which causes the shaft 34 to rotate with one or the other of such driven means 32 and 33. This arrangement offers a selectivity of different speeds of the shaft 34 with respect to the shaft 28. A driving means 39, which is rigidly 50 supported on the shaft 34, actuates the driven means 40 on the shaft 41 by means of the chain or other like power transmitting means 42. Loosely supported on the shaft 41 are the driving 55 means 43 and 44, which may be respectively caused to rotate with the shaft 41 by the engagement of the proper frictional driving means with the drums associated with the driving means 43 and 44 to rotate the shaft 56 either through the idler member 51 from the gear 43 or directly from the gear 44, thus causing shaft 60 56 to turn in the same direction with shaft 41, or in the opposite direction. The shaft 56, through the medium of the driving and driven means 57 and 58, respectively, revolubly actuates the shaft 93, which, in turn, propels the carriage by rotating the wheels thereof as hereinbefore described. The shaft 41 has also rigidly secured thereto a driving means 59, which revolubly actuates the driven means 60 and 61 which are respectively rigidly mounted on the shafts 62 and 63, respectively.

Loosely mounted on the shafts 62 and 63, respectively, are winding spools 64 and 65, adapted to receive the hoisting cables which run through 70 blocks 11 and 12, respectively. When it is de-

sired to rotate either of these spools to wind up the cable thereon, the spools 64 and 65 are frictionally engaged with gears 60 and 61, and are caused to rotate respectively with the shafts 62 and 63.

5 The driven means 60, which also serves as a driving means for the driven means 73 rigidly supported on the shaft 74, causes such shaft 74 to rotate and the winding spools 88 and 89 are, in turn, caused to rotate in either direction by axially moving the clutching elements 79 and 80 to engage the oppositely disposed driving means 75 and 76, which cause rotation of the shaft 87 through the medium of the driven means 83 and the driving means 85, depending upon which one 10 of such means 75 or 76 is in engagement with the driven means 83. By turning the drums 88 and 89 in one direction the boom 1 is raised; by reversing the direction of the drums the boom 1 is lowered.

15 For causing rotation of the revoluble bed 2 of the machine, the shaft 62, which is caused to rotate by means of the driven means 60, has mounted thereon oppositely disposed driving means 70 and 71, either of which may be caused to revolve 20 with the shaft 62 by a proper operation of clutches 70' and 71' and the selected one of the driving means 70 or 71 through which the power is transmitted, causes the beveled driven means 72 to revolve in a predetermined direction, thereby 25 causing the bed 2 to rotate with respect to the carriage frame 16.

30 As hereinbefore explained, when the boom is supporting a load on the cables 13 or 13', such load being sufficiently heavy to overcome the 35 equilibrium of the bed 2, the bed 2 is caused to be inclined slightly from its horizontal position on the carriage 16. When the bed 2 is so caused to incline, the king bolt 93' which passes through the axis of rotation of the bed 2 will be cramped 40 and will have a tendency to bind in the casting 114 unless some means is provided for permitting the casting 114 to freely rotate on the king bolt 93', regardless of the inclination of the bed 2. The means for permitting free rotation of 45 casting 114 on king bolt 93' is illustrated in Figs. 4 and 5. It will be seen from an examination of these figures that when the bed 2 is inclined from the horizontal, the sills 20 and 21, which form 50 an integral part of such bed, are displaced in like manner and the member 114 tends to bind on king bolt 93'. The tendency of member 114 to bind on king bolt 93' is suitably overcome by means of the rollers 116 bearing against the king bolt 93'. 55

Vertical displacement of the axis of the revoluble bed 2 which may be caused by an excessive load on the boom 1, which would have a tendency to rotate the bed 2 about its portion adjacent the lower end of the boom 1, is also restrained by 60 means of the king bolt 93'. The attempted vertical movement of the revoluble bed 2 at its central portion due to the stresses set up, as hereinbefore explained, is counteracted by the collar 121 bearing against the thrust bearing 120 carried by the block 119 in the member 114, which is rigidly united with the sills 20 and 21 forming an integral portion of the revoluble bed 2. As the axis of the tipping of bed 2 and its attached casting 114 is always transverse, that is, at right 65 angles to a line passing through the center of the bed 2 and the boom 1, the lower bearing surface of the block 119 is in the form of a segment of a cylinder, the axis of the segment of the cylinder being parallel to the axis of inclination of the 70 75

bed. Thus an even pressure is exerted on each of the numerous balls in the bearing 120.

The construction of the king bolt 93 and its associated parts is therefore seen to permit the free rotation of the bed 2 regardless of the stresses to which the bed 2 may be subjected, due to a load which may be desired to be supported by the cables 13 and 13'.

The construction of the revoluble bed 2 of the machine and more especially the arrangement of the various parts with respect to the sills 20 and 21, permits such sills to carry practically all of the main stresses incidental to the manipulation of the boom and the loads which such boom is called upon to carry. The members 23 which are integrally united with the terminal portions of such sills, lie in alignment with the webs of such sills and transmit the stresses directly thereto without in any way subjecting the rest of the bed 2 to any of such stresses, permitting the bed 2 to be of relatively light construction excepting the two sills which carry the major portion of the load. The means for revolving the bed, which, as shown in Fig. 3, are mounted on the shaft 62 are also supported by rigid members framed into the sill 20, thereby permitting such sill to carry the major portion of the stress and preventing the stress due to the rotation of such bed from being transmitted to the other frame members comprising the bed.

Supporting the conical rollers, in the manner illustrated in Fig. 6, by means of the brackets 134 which are trunnioned on the shafts 135, gives a three point suspension for the revoluble bed 2, and assures the proper load for each conical roller. The arrangement of the rockers in three groups is shown in Fig. 3.

A further description of this machine is deemed unnecessary for those acquainted with the art; suffice it is to say that changes may be made in the construction and arrangement of the various operating parts comprising this invention without materially departing therefrom and the results attained by the general layout of the various parts of the machine and their correlated elements effects advantages not possible with constructions now in use.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:

1. In a machine of the character described, the combination of a carriage, a vertically extending tubular member rigidly associated with the frame of said carriage, a revoluble frame structure supported on said carriage and normally parallel therewith, a friction reducing bearing interposed between said revoluble frame structure and the radially outer wall of said tubular member and means for assuring a substantially even pressure on said bearing when the revoluble frame is slightly inclined from its parallel position in relation to said carriage.

2. In a machine of the character described, the combination of a carriage, a vertically extending tubular member rigidly associated with the frame of said carriage, a revoluble frame structure supported on said carriage and normally parallel therewith, a friction reducing bearing interposed between said revoluble frame structure and the radially outer wall of said tubular member, and

a block associated with said revoluble frame structure and revoluble therewith about said tubular member, said block having a curved lower surface against which said frame structure bears and upon which it may rock when the revoluble frame is slightly inclined from its parallel position in relation to said carriage so as to assure a substantially even pressure on said bearing.

3. In a machine of the character described, the combination of a mobile carriage, a boom supporting frame revolubly mounted on said carriage and normally parallel therewith, a drive shaft extending through said carriage and said revoluble frame structure, a tubular element encompassing said drive shaft and rigidly secured to said carriage, a friction reducing bearing interposed between said tubular element and said frame, and means associated with said boom supporting frame and revoluble therewith about said tubular member, said means assuring a substantially even pressure on said bearing when the revoluble frame is slightly inclined from its parallel position in relation to said carriage.

4. In a machine of the character described, the combination of a mobile carriage, a boom supporting frame revolubly mounted on said carriage and normally parallel therewith, a drive shaft extending through said carriage and said revoluble frame structure, a tubular element encompassing said drive shaft and rigidly secured to said carriage, a friction reducing bearing interposed between said tubular element and said frame, and a block associated with said boom supporting frame and revoluble therewith about said tubular member, said block having a lower surface in the form of a segment of a cylinder and against which said boom supporting frame bears when the revoluble frame is slightly inclined from its parallel position in relation to said carriage, so as to assure a substantially even pressure on said bearing.

5. In a machine of the character described, the combination of a carriage, a tubular member rigidly associated with the frame of said carriage, a boom supporting frame mounted on and normally parallel with said carriage and revoluble about said tubular member, means for limiting axial movement of said boom supporting frame with respect to said tubular member, a ball bearing interposed between said boom supporting frame and limiting means, and means interposed between said boom supporting frame and bearing for assuring a substantially even pressure against the balls of said bearing when the boom supporting frame is slightly inclined from its parallel position in relation to said carriage, so as to prevent overloading of any of said balls.

6. In a machine of the character described, a carriage, a platform rotatably supported on said carriage, said platform being tiltable in the direction of the load when eccentrically loaded, a king-pin tying the platform to the carriage at the axis of rotation of the platform while leaving the platform free to rotate, a bearing collar encircling said king-pin and carried by said platform restraining it from excessive tipping or rocking movement, a thrust bearing encircling said king-pin reducing friction between said carriage and said platform, and a tension block rotatably mounted on said king-pin between said collar and said bearing and held against rotation relative to said collar, said block having a cylindrical face bearing against said collar on a

line transverse to the direction of tilt of said platform.

7. In a machine of the character described comprising a carriage and a platform rotatably supported on the carriage, said platform being tilttable in the direction of the load when eccentrically loaded, in combination a king-pin tying the platform to the carriage at the axis of rotation of the platform while leaving the platform free to rotate, a bearing collar encircling said king-pin, which collar is carried by the platform and restrains it from excessive tip-

ping or rocking movement, a thrust bearing encircling said king-pin adapted to reduce friction between the carriage and the platform, and a tension block rotatably mounted on said king-pin between said collar and said bearing and held against rotation relative to said collar, said block having a cylindrical face bearing against said collar on a line transverse to the plane defined by movement of the tilttable platform.
